ZIGZAG STITCHING MACHINE

Wilhelm Böltter, Bielefeld, Germany, assignor to
Anker-Werke, A. G., Bielefeld, GermanyApplication November 22, 1934, Serial No. 754,301
In Germany November 23, 1933

23 Claims. (Cl. 112—159)

The instant invention relates to sewing machines embodying a zigzag stitch forming mechanism. The object of the invention is to provide such a sewing machine for household purposes which is particularly economical to produce and which however operates simply and with certainty.

It is one of the features of the invention to adapt to such a machine a shuttle having an oscillating movement of the type known as an oscillating shuttle, which is cheaper than the rotary hook type.

It has been proposed previously to employ such a shuttle in zigzag stitch forming machines so that the shuttle carrier is arranged in the longitudinal axis of the machine, so that the needle bar swings in the direction of movement of the shuttle point. This arrangement has the disadvantage that the transmission of the oscillating driving movement to the shuttle involves too costly and complicated transmission elements, and aside from this, that the extraction of the shuttle from its housing is inconvenient.

In accordance with the instant invention, the use of an oscillating shuttle for such a machine is attained by arranging the shuttle housing so that it executes an oscillating movement coincidentally with the movement of the needle bar, although in the usual manner they are arranged transversely. Another feature of the invention resides in the regulation of the lateral swinging of the shuttle housing from the same setting elements which adjust the lateral swing of the needle bar.

In accordance with the particularly advantageous construction of the illustrative machine described herein, it is possible to attain in a household zigzag stitch-forming machine, a controllable setting for the direction of the throw of the needle from its mid-position, as well as for the extent of the lateral throw of the needle. This is attained by an arrangement, for the regulation of the lateral throw of the needle-bar by means of a grooved block eccentrically mounted in a rotatable member. As a result of this arrangement, the extent of the lateral throw may be controlled by the setting of the groove in known manner, while as a new result, the direction of the throw of the needle from its mid-position is regulated by a special setting lever.

Two different embodiments of the invention are illustrated, namely; one embodiment in which the shuttle housing and thereby the point of the shuttle describes a downwardly directed open arc, and another embodiment in which the shuttle housing

and thereby the point thereof describes an upwardly directed open arc.

In accordance with the second embodiment, while retaining the main feature of the invention concerning the oscillating movement of the shuttle housing, the shuttle housing is itself swingingly suspended, so that the point of the movable shuttle in the housing describes an upwardly directed open arc, while the driver of the shuttle does not partake of this swinging movement, receiving only an axial shifting. In combination with the new arrangement, the forked connecting rod for transmitting the oscillating movement to the needle frame is arranged above the top shaft of the sewing machine arm.

By this arrangement, the advantages attained over the first embodiment of the invention and furthermore over other known zigzag stitch forming machines with horizontally shiftable shuttle housings, is that the danger of the skipping of stitches is eliminated. This advantage arises from the fact that the shuttle point here is lifted against the loop so that the formation of the loops in the end positions is rendered easier.

By means of the displacement of the forked connecting rod for the drive of the needle-bar above the top shaft, the opening under the horizontal bracket-arm is not constricted at the curve merging into the vertical portion of the machine arm.

It is known in zigzag stitch forming machines to displace the starting point of the lateral throw of the needle.

In accordance with the instant invention, the displacement of the starting position of the lateral swing of the needle is obtained by shifting laterally the pivot point of the grooved block for the stitch regulator, by means of an eccentric, through half the extent of the maximum width of the stitch. Thereby the advantage is attained that a slot of smaller extent in the stitching plate suffices for all cases.

In accordance with the invention, a plate is inserted in the sewing machine arm in which, according to the arrangement in the first embodiment, is provided a rotatable member. A bolt is eccentrically arranged in this rotatable member which transmits the adjusting movement to the groove, in known manner, for the purpose of regulating the size of the stitch. Since the setting lever for determining the direction of the throw of the needle-bar is connected with the rotatable member and since the setting lever for regulating the width of stitch is mounted on the eccentrically disposed bolt, the setting device may be

inserted in the sewing machine arm as a complete unit. In accordance with the invention, a protecting cap is mounted over the setting lever which is screwed upon the plate carrying the setting lever. The opening for the setting lever in this cap is provided at the same time with a setting device for the setting lever formed according to the invention from a resilient steel yoke for regulating the width of the stitch.

10 The first embodiment of the invention is illustrated in Figs. 1-3, the second embodiment in Figs. 4-7, while Figs. 8-11 show a particularly advantageous form of setting means which may be applied to the sewing machine arm.

15 In the drawings:

Figure 1 shows schematically a front view of the first embodiment of the invention,

Figure 2 is a plan view of a part of Figure 1, as well as Figure 4,

20 Figure 3 is a sectional view through the machine at the regulating mechanism, showing the elements thereof in accordance with the first embodiment of the invention,

25 Figure 4 is a view corresponding to Figure 1 of the second embodiment of the invention,

Figure 5 is a sectional view corresponding to Figure 3 of the second embodiment of the invention,

30 Figure 6 is a front view of the head of the forked rod shown in Figures 4 and 5.

Figure 7 is a diagram showing the control of the width of the stitch according to the embodiment shown in Figures 4-6,

35 Figure 8 is a front view of the arrangement of the setting means,

Figure 9 is a sectional view along line 9-9 of Figure 8,

Figure 10 is a plan view of Figure 8,

40 Figure 11 is a side view of the protecting cap shown in Figure 8, and

Figure 12 is a detail elevation of the shuttle head shown in Fig. 1, taken from the left.

In reference to the embodiment of the invention illustrated in Figures 1-3, the frame 1 carrying the needle bar is mounted to pivot about a point 2 and is capable of assuming the designated end positions from the mid-position shown schematically in Figure 2. The lateral swinging of the needle frame is effected by means of forked lever 3, the fork 4 of which embraces an eccentric 6 mounted upon shaft 5. The eccentric 6 is driven in known manner from the top shaft of the sewing machine. The forked rod 3 carries a guide block 21 which is guided in known manner in a guide groove 7 of the grooved block 8. The block 8 is adjustable in known manner by means of an adjusting lever 9 whereby the extent of the lateral swinging movement of the needle is regulated.

60 In accordance with the invention, the grooved guide block 8 is eccentrically mounted in a bush 10 which is rotatably arranged in the machine arm 11. The bush 10 is connected with a lever 12 which preferably has three positions.

65 A pin 13 is connected with the block 21, which is movable in guide groove 7, which pin extends through a bore in the forked end 4 of connecting rod 3. This pin is furthermore embraced by a longitudinal slot 14 of double armed lever 16 pivoted upon pin 15. The lower arm of lever 16 is jointedly connected to one end of draft rod 17, the other end of which engages the shuttle housing 18. The shuttle housing 18 is pivotally mounted upon two pins 19.

The apparatus described above operates in the following manner:

By means of the setting lever 12 and the rotation of the bush 10 thereby, the pivotal point of the grooved block 8 may be shifted so that the needle frame 1 and, together therewith, the shuttle housing 18 execute either an oscillating movement on both sides of their mid-positions or these elements execute an oscillating movement on one or the other side of their mid-positions. By 10 means of the setting lever 9, the extent of the lateral throw of these elements from their mid-positions may be regulated in known manner.

In the embodiment shown in Figures 4-7, the needle frame 1 carrying the needle bar is mounted to pivot about a point 2 and is capable of assuming the end positions from the indicated mid-position shown in Figure 2. The lateral swinging movements of the needle frame 1 are generated by means of the forked rod 3, the fork 20 4 of which embraces an eccentric 6 mounted upon shaft 5. The eccentric 6 is driven in known manner from the top shaft of the sewing machine. The forked rod 3 carries in a projection of its fork 4, a block 21 which is guided in a groove 7 of the guide block 8 in known manner. The block 8 is adjustable, in known manner, through its bolt 22 by means of setting lever 9, whereby the extent of the lateral swinging movement of the needle may be regulated. The bolt 30 22 connected with the block 8 is mounted eccentrically in bush 10, which in turn is rotatably disposed in machine arm 11. The bush 10 is rigidly connected with lever 12 whereby the former may be adjusted by the latter in different positions. Three settings for the lever 12 are possible, whereupon from time to time use is made of the mid-position setting and either one of the end settings. A pin 13 is connected with the block 21, movable in guide groove 7, which pin extends through a bore in fork 4 of rod 3 (Figs. 5 and 6). A longitudinal slot 14 (Fig. 4) of a double-armed lever 16 embraces the pin 13. The double-armed lever 16 is pivoted upon pin 15 and is furthermore jointedly connected with another double-armed lever 23 which is pivoted upon pin 24 and which is jointedly connected with one end of draft rod 17. The draft rod 17 engages with a transverse yoke 25 of a sleeve 26, which is axially shiftable in a bearing 27 cast on the machine plate 28, and which is connected with the actuator 29 of the shuttle so that the latter partakes of the axial shifting movement of the sleeve. A drive shaft 31 is mounted in the bore of the sleeve 26 which is coupled by means of a coupling 32 with a drive shaft 33 for oscillating movement. The transverse yoke 25 is jointedly connected at its lower end with a link 34 rigidly connected with the shuttle housing. The link 34 is furthermore guided by means of a guiding projection 36 on the bearing 27. The shuttle housing 35 is swingingly suspended by means of two hanging arms 36 on the underside of the sewing machine plate.

The mode of operation of the apparatus described above may be explained by the following:

The pivot point of the bush 10 in the machine arm 11 is so chosen in accordance with the invention that the rotation of this bush shifts the pivot point 22 of the guide block 8 along a line 70 parallel to line I-II in Fig. 7, whereas in the arrangement according to Figs. 1-3 a displacement of the pivot point along a line parallel to line I-III takes place. The line extending from point 1 in Figure 7 corresponds to the forked 75

connecting rod 3. It is apparent from Figure 7 that according to the new kinematic relation of the parts the starting point of the lateral throw of the needle bar is displaced to the left by 5 means of lever 12 to an extent equivalent to

$$\frac{a}{2}$$

so that instead of the middle stitch diagram in 10 Figure 7 which is common to the embodiment shown in Figures 1-3 as well as to that shown in Figures 4-6, the diagram immediately below the common diagram or the second one from the bottom in Figure 7 is obtained. By the regulation 15 of the width of the stitch by means of lever 9, the lateral swing of the needle bar may be diminished to zero so that a straight closing seam results. Instead of a displacement of the pivot point of the grooved block to the left, it is 20 possible to displace it to the right with reference to its mid-position, in accordance with the upper control triangle, in which case instead of the lower withdrawn setting for the lever 9, the upper withdrawn position is used, or else the bush 25 10 is itself shiftably arranged in the machine arm 11. In contrast to the arrangement shown in Figures 1-3 in which the needle may be swung either to one side or to the other side, a shortening of the slot in the stitching plate, which may 30 be used for all cases, is attained hereby.

The insertion of the adjusting mechanism in the sewing machine arm may be effected in the manner illustrated in Figures 8-11, as described in detail below:

35 The same parts which are shown in the embodiments described above are designated by like reference characters. Therefore, the rotatable body 10 in the novel arrangement disclosed in these figures is illustrated as rotatably mounted 40 in a plate 31', which is fastened to the sewing machine arm by screws 32'. A bolt 33' is rotatably mounted within the rotatable body 10 and the guide block 8 is rigidly connected with the former. The setting lever 9 is fixed upon the 45 front end of bolt 33' and is built in the form of a resilient steel yoke which in known manner effects an adjustment of the width of the zigzag stitch by rotation of the guide block 8. The lever 9 is maintained in its adjusted position by means of a cap or supplementary plate 50 35' which is screwed into the plate 31' with screws 34' leaving an opening 36'' for the lever 9, which opening is provided with a toothed edge formed by small notches 37. The nose 38 of lever 9 resiliently engages these notches (Figs. 55 10 and 11). A scale is provided on the outside of plate 35' over the toothed edge, and a projection bent from the lever 9 cooperates therewith as an indicator for the setting adjustments.

60 The setting lever 12 is rigidly connected with the rotatable body 10 which, as shown in Figure 8, extends from the upper edge of the cap 35' and which may assume the position shown in dotted lines in Figure 8 in addition to that shown 65 in solid lines in this figure. The shifting of the lever 12 in one or the other of its setting positions determines the field of oscillation of the needle, as described above.

In view of the fact that the invention described 70 above and illustrated in Figures 8-11 is not limited in its application to a stitch forming mechanism embodying an oscillating shuttle housing, the mechanism for transmitting the oscillating movement to the shuttle housing is not illustrated in these figures. In accordance with the

arrangement shown in the embodiment in Figures 1-3, Figures 9 and 10 show a shaft 5 mounted in the sewing machine arm 11 on which is fixed an eccentric 6 which is embraced by the fork 4 of the forked connecting rod and which 5 furthermore is driven in known manner from the upper shaft of the machine. This fork 4 has, corresponding to the embodiments described above, a projection 39 in which is riveted a pin 10 13 which engages in the grooved block 8.

Having described my invention, what I claim is:

1. In a sewing machine, particularly for household use, a zigzag stitch forming mechanism comprising a shuttle housing mounted for oscillatory movement about a horizontal axis perpendicular to the longitudinal axis of the machine, a shuttle in said housing, means to impart an oscillatory movement to said shuttle, a needle bar, a rod for oscillating said needle bar 20 transversely of its axis, and driving means for actuating said rod and for imparting an oscillating movement to said housing concomitantly with the movement of said needle bar.

2. In a sewing machine, particularly for household use, a zigzag stitch forming mechanism comprising a shuttle housing mounted for oscillatory movement about a horizontal axis perpendicular to the longitudinal axis of the machine, a shuttle in said housing, means to impart an oscillatory movement to said shuttle, a needle bar, an actuating rod for laterally oscillating said needle bar, driving means for actuating said rod and for imparting an oscillating movement to said housing concomitantly with the 35 movement of said needle bar, and common regulating means for controlling the oscillating movement of said needle bar and said shuttle housing.

3. The combination claimed in claim 2 where- 40 in said common regulating means comprises a rotatable member, and a grooved block mounted eccentrically in said member.

4. The combination claimed in claim 2 where- 45 in said common regulating means comprises a rotatable member, a regulating lever connected with said member for adjusting the field of the oscillating movement of said needle bar, a grooved block mounted eccentrically in said member, and a regulating lever for adjusting 50 the setting of said block for controlling the extent of oscillating movement of said needle bar.

5. The combination claimed in claim 2 wherein 55 said common regulating means comprises a rotatable member disposed in the sewing machine arm, a regulating lever connected with said member for adjusting the field of the oscillating movement of said needle bar, a bore disposed eccentrically in said member, a bolt in said bore, a grooved block at the end of said bolt, and a sec- 60 ond regulating lever connected with said bolt for adjusting the setting of said block for controlling the extent of oscillating movement of said needle bar.

6. In a sewing machine, particularly for household use, a zigzag stitch forming mechanism comprising a shuttle housing, a needle bar, an actuating rod for laterally oscillating said needle bar, driving means for actuating said rod and for imparting an oscillating movement to said housing concomitantly with the movement of said needle bar, and common regulating means for controlling the oscillating movement of said needle bar and said shuttle housing, said regulating means comprising a rotatable member dis- 65 70 75

- posed in the sewing machine arm, a regulating lever connected with said member for adjusting the field of the oscillating movement of said needle bar, a bore disposed eccentrically in said 5 member, a bolt in said bore, a grooved block at the end of said bolt, and a second regulating lever connected with said bolt for adjusting the setting of said block for controlling the extent of oscillating movement of said needle bar, a lug 10 on said actuating rod engaging the groove in said grooved block, a pin connected with said lug, and a double armed lever having one arm thereof connected with said shuttle housing and the other arm terminating in a longitudinal slot embracing 15 said pin.
7. In a sewing machine, particularly for household use, a zigzag stitch forming mechanism comprising a shuttle housing, a needle bar, an actuating rod for laterally oscillating said needle bar, 20 driving means for actuating said rod and for imparting an oscillating movement to said housing concomitantly with the movement of said needle bar, and common regulating means for controlling the oscillating movement of said 25 needle bar and said shuttle housing, said regulating means comprising a rotatable member disposed in the sewing machine arm, a regulating lever connected with said member for adjusting the field of the oscillating movement of said 30 needle bar, a bore disposed eccentrically in said member, a bolt in said bore, a grooved block at the end of said bolt, and a second regulating lever connected with said bolt for adjusting the setting of said block for controlling the extent of 35 oscillating movement of said needle bar, an extension on said actuating rod at the end thereof opposite the needle bar, a lug on said extension engaging the groove in said grooved block, a pin connected with said lug, and a double-armed 40 lever having one arm thereof connected with said shuttle housing and the other arm terminating in a longitudinal slot embracing said pin.
8. In a sewing machine, particularly for household use, a zigzag stitch forming mechanism 45 comprising a needle bar, a rod for oscillating said needle bar transversely of its axis, a plate below said needle bar, a pair of arms swingingly suspended from the underside of said plate, a shuttle housing carried by said arms, a shuttle 50 in said housing, the point of said shuttle describing an upwardly open arc as said housing swings, and driving means for actuating said rod, and connections between said driving means and said shuttle housing for imparting an oscillating 55 movement to the latter concomitantly with the movement of said needle bar.
9. In a sewing machine embodying an arm, particularly for household use, a zigzag stitch forming mechanism comprising a shuttle housing, a 60 needle bar, an actuating rod for laterally oscillating said needle bar, driving means for actuating said rod, connections between said driving means and said shuttle housing for imparting an oscillating movement to said housing con- 65 comitantly with the movement of said needle bar, and common regulating means for controlling the oscillating movement of said needle bar and said shuttle housing comprising a rotatable member, a plate for retaining said mem- 70 ber, an opening in said sewing machine arm for receiving said plate, a regulating lever connected with said member for adjusting the field of the oscillating movement of said needle bar, a bore disposed eccentrically in said member, a bolt in 75 said bore, a grooved block at the end of said bolt,

and a second regulating lever connected with said bolt for adjusting the setting of said block for controlling the extent of oscillating movement of said needle bar.

10. The combination claimed in claim 9 where- 5 in a supplementary plate is superposed over said member retaining plate and over said regulating levers, and means on said supplementary plate for holding at least one of said regulating levers in its adjusted position. 10

11. The combination claimed in claim 9 where- 15 in one of said regulating levers is formed resil- 15. iently, a supplementary plate superposed over said member retaining plate and over said regulating levers, and a toothed portion on said sup- 15. plementary plate cooperating with said resilient lever to maintain said lever in its adjusted position.

12. The combination claimed in claim 9 where- 20 in one of said regulating levers is formed resil- 20. iently, a supplementary plate superposed over said member retaining plate and over said regulating levers, a toothed portion on said supplementary plate cooperating with said resilient lever to 25 maintain said lever in its adjusted position, a scale on the outside of said supplementary plate adjacent said toothed portion, and a projection bent from said resilient regulating lever in prox- 25. imity to said scale.

13. In a sewing machine, particularly for 30 household use, a zigzag stitch forming mecha- 30. nism comprising a needle bar, a rod for oscillat- 35 ing said needle bar transversely of its axis, a shuttle housing, a shuttle in said housing, said shuttle housing being swingingly suspended be- 35. low said needle bar, whereby the point of said shuttle moves along an upwardly open arc as said housing swings, driving means for actuating said rod, and connections between said driving means and said shuttle housing for swinging the 40 latter concomitantly with the movement of said 40. needle bar.

14. In a sewing machine, particularly for house- 45 hold use, a zigzag stitch forming mechanism com- 45. prising a needle bar, a rod for oscillating said needle bar transversely of its axis, a shuttle 50 housing, a shuttle in said housing, said shuttle housing being swingingly suspended below said needle bar, whereby the point of said shuttle moves along an upwardly open arc as said hous- 50. ing swings, an axially movable actuator for oscillating said shuttle in said housing, driving means for actuating said rod, and connections between said driving means and said shuttle 55 housing for swinging the latter, said connec- 55. tions having means engaging said shuttle actuator to shift the same axially.

15. In a sewing machine, particularly for household use, a zigzag stitch forming mecha- 60 nism comprising a needle bar, a rod for oscillat- 60. ing said needle bar transversely of its axis, a shuttle housing, a shuttle in said housing, said shuttle housing being swingingly suspended be- 65 low said needle bar, whereby the point of said shuttle moves along an upwardly open arc as said hous- 65. ing swings, a sleeve movable axially sub- stantially in the direction in which said housing swings, a drive shaft mounted to oscillate in said sleeve, an actuator on said drive shaft for oscillating said shuttle in said housing, said shaft 70 and actuator being movable axially with said sleeve, driving means for actuating said rod, and connections leading from said driving means to said sleeve and to said shuttle housing for im- 70. parting axial movements to the former and 75

swinging movements to the latter, concomitantly with the movement of said needle bar.

16. In a sewing machine, particularly for household use, a zigzag stitch forming mechanism comprising a needle bar, a rod for oscillating said needle bar transversely of its axis, a shuttle housing, a shuttle in said housing, said shuttle housing being swingingly suspended below said needle bar, whereby the point of said shuttle moves along an upwardly open arc as said housing swings, a sleeve movable axially substantially in the direction in which said housing swings, a drive shaft mounted to oscillate in said sleeve, an actuator on said drive shaft for oscillating said shuttle in said housing, said shaft and actuator being movable axially with said sleeve, a transverse yoke connected to said sleeve at the end thereof opposite said actuator, eccentric driving means for actuating said rod, connections between said eccentric and said yoke for imparting axial movements to said sleeve, and means for transmitting movements to said shuttle housing concomitantly with the movement of said needle bar.

17. A sewing machine as described in claim 16, wherein said means for transmitting movements to said shuttle housing comprises a link extending between the lower end of said transverse yoke and said shuttle housing.

18. A sewing machine as described in claim 16, wherein said means for transmitting movements to said shuttle housing comprises a link extending between the lower end of said transverse yoke and said shuttle housing, said sleeve being mounted in a bearing, said link being guided in a groove in said bearing.

19. In a zigzag stitch sewing machine, a horizontal bracket, a main driving shaft in said bracket, a needle bar mounted on said bracket so as to oscillate transversely to its axis, a rod disposed above said main driving shaft in said bracket and connected to said needle bar for oscillating the same, an eccentric for imparting

up and down movements to the end of said rod remote from said needle bar, said remote end of said rod having a downward projection bearing a guide follower, a guide for said follower mounted on said bracket, a swinging shuttle housing, and connections between the downward projection of said rod and said shuttle housing, said guide being adapted to impart axial motions to said rod to swing said needle bar and said shuttle housing concomitantly.

20. A sewing machine as described in claim 19, wherein said connections between said downward projection and said shuttle housing comprise two first class levers jointed together, the remote end of one lever being connected to said shuttle housing, the remote end of the other lever being provided with a slot, said downward projection bearing a bolt extending through said slot.

21. A sewing machine as described in claim 15, 20 wherein said drive shaft is divided into two parts connected by a coupling permitting relative axial movement of said parts, one of said parts extending through said sleeve and the other being connected to the main drive of the machine. 25

22. A sewing machine as described in claim 13, wherein said driving means comprises an eccentric for swinging the end of said rod remote from said needle bar up and down, a pivotally mounted guide block having an inclined guide groove, a 30 follower on said rod travelling in said groove to reciprocate said rod longitudinally, and means for adjusting the position of the pivot of said guide block along an inclined line.

23. A sewing machine as described in claim 2, 35 wherein said common regulating means comprises a rotatable member, a grooved block mounted eccentrically in said member, and a plate on which said rotatable member is mounted, the bracket arm of the machine having an 40 opening in which said plate is removably secured.

WILHELM BÖLTER.
